DESIGN FOR A REFLECTOR JEWEL

Samuel Kaplan, New York, N. Y.

Application August 5, 1933, Serial No. 48,927

Term of patent 3½ years

To all whom it may concern:

Be it known that I, SAMUEL KAPLAN, a citizen of the United States, residing at New York city, county of Bronx, State of New York, have invented a new, original, and ornamental Design for Reflector Jewel, of which the following is a specification, reference being had to the accompanying drawing, forming a part thereof, and in which

Fig. 1 is a front face view of a reflector jewel showing my new design,

Fig. 2 is a vertical section through the center of the jewel, and

Fig. 3 is a view of the rear face of the jewel.

The dominant feature of the design resides in a honey-comb arrangement of convex-surfaced facets, on the concaved rear face of the jewel.

I claim:

The ornamental design for a reflector jewel as shown and described.

SAMUEL KAPLAN.
